US0D1055917S

(12) **United States Design Patent** (10) Patent No.: **US D1,055,917 S**
(45) Date of Patent: ** Dec. 31, 2024

(54) **WEARABLE DEVICE WITH GRAPHICAL USER INTERFACE**

(71) Applicant: **Apple Inc.**, Cupertino, CA (US)

(72) Inventors: **Molly Anderson**, San Francisco, CA (US); **Guillaume P. Barlier**, Sunnyvale, CA (US); **Kevin Will Chen**, Cupertino, CA (US); **Andrew Patrick Clymer**, San Jose, CA (US); **Clara Geneviève Marine Courtaigne**, Palo Alto, CA (US); **Hanwen Fan**, San Jose, CA (US); **Lynnette Lucille Galloway**, Culver City, CA (US); **Aurelio Guzmán**, San Jose, CA (US); **Andre Ricardo Jointe**, Woodlands Hills, CA (US); **Gilbert Esrome Kuruneri**, San Francisco, CA (US); **Bobby Cole Martin, Jr.**, Palo Alto, CA (US); **Dana R. Mason, Jr.**, San Francisco, CA (US); **Michael Tettey Nartey**, San Jose, CA (US); **Oladapo Onikuyide**, San Francisco, CA (US); **Clement Tissandier**, San Francisco, CA (US); **Vincenzo Vuono**, Sunnyvale, CA (US)

(73) Assignee: **Apple Inc.**, Cupertino, CA (US)

(**) Term: **15 Years**

(21) Appl. No.: **29/882,676**

(22) Filed: **Jan. 17, 2023**

(51) LOC (14) Cl. **14-02**

(52) U.S. Cl.

USPC **D14/344**; D10/70; D24/186

(57) **CLAIM**

The ornamental design for a wearable device with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a wearable device with graphical user interface showing the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a left rear perspective view thereof;

FIG. 8 is a right front perspective view thereof;

(Continued)

FIG. 9 is a right rear perspective view thereof; and, FIG. 10 is a left front perspective view thereof.

**1 Claim, 10 Drawing Sheets
(10 of 10 Drawing Sheet(s) Filed in Color)**
